UNITED STATES PATENT OFFICE.

MARTINUS H. G. OEDEKERK, OF LEBANON, INDIANA, ASSIGNOR TO THE DAIRY CREAM SEPARATOR CO., OF LEBANON, INDIANA.

CENTRIFUGAL SPEEDOMETER FOR SEPARATORS.

1,136,706.

Specification of Letters Patent.

Patented Apr. 20, 1915.

Application filed May 16, 1914. Serial No. 839,041.

To all whom it may concern:

Be it known that I, MARTINUS H. G. OEDEKERK, a citizen of the United States, residing at Lebanon, in the county of Boone and State of Indiana, have invented a new and useful Centrifugal Speedometer for Separators, of which the following is a specification.

My invention relates to centrifugal speedometers and has for its particular object the indicating of the speed at which the shaft of a cream separator is rotating.

It is an especial object of my invention to provide a speedometer which does not require any spring or other resilient element as one of its members; to provide a device of improved and simplified construction operating in a novel manner to indicate the speed at which the center shaft of a cream separator is rotating; and to provide a device that is durable, will not easily get out of order and which may be manufactured at less expense than speedometers heretofore devised of this class. I attain these objects by the mechanism illustrated in the accompanying drawings, in which—

Figure 1 is a front elevation of my invention applied to a centrifugal separator; Fig. 2 is a side elevation of same; Fig. 3 is a cross section on line 3—3 of Fig. 1.

Similar letters refer to similar parts throughout the several views.

Referring to the accompanying drawings, A indicates a dial plate having appropriate graduations to indicate speed of rotation of the center shaft J of the separator.

B indicates a finger by which the speed is indicated. Finger B is mounted on pivot C, and connected by connecting member L to a vertically slidable connecting rod D, mounted in sleeve E. Connecting rod D has its lower end supported by a vertically movable disk member F, which in turn is mounted on center shaft J of the separator. Eng-

aging with the bottom portion of disk member F and adapted to transmit a vertical movement to it are opposite centrifugal elements indicated by the letters H and G, each of the elements consisting of a weighted portion H pivoted at I to the center shaft J and having an arcuate lever portion G, integrally formed with H, arcuate edges K being disposed to support and raise or lower disk member F. I provide

a suitable pivot C on which finger B is

mounted and adapted to be adjusted, and a suitable clamping nut C' on the pivot adapted to secure finger B in any desired adjusted position from time to time as may be necessary. As indicated by the drawings, this device is built in and directly connected with the center shaft of centrifugal separators.

In the operation of this speedometer, it will be observed that springs have been eliminated, and that in its operation the centrifugal movement of the elements indicated by H and G, which are pivotally connected with the center shaft, raise disk member F, as the speed is increased, which in turn raises connecting rod D and connecting member L and gives a rotary movement to finger B, the return of the various members to their original position when speed slackens being effected by gravity.

The accompanying drawings are illustrative of my invention, but minor changes in details of construction and arrangement of parts not constituting an essential departure from the disclosure are within the contemplation of my invention.

What I claim is:

1. A centrifugal speedometer comprising opposite centrifugal elements each having a weighted portion and an arm with an arcuate edge portion, a disk member supported by the centrifugal elements, a separator center shaft to which the centrifugal elements are pivoted and on which the disk member is mounted, a connecting rod having its bottom end supported and actuated by the disk member, a sleeve in which the aforesaid connecting rod is vertically movable, a graduated plate member, a speed-indicating finger pivotally mounted thereon, and means connecting the aforesaid finger with the above-mentioned connecting rod, substantially as set forth.

2. The combination with a center shaft of a dial plate, a speed indicating finger pivotally mounted on the dial plate, a disk member mounted on the center shaft and free to move vertically thereon, substantially vertically-disposed gravity-controlled members operatively connecting the disk member and the speed-indicating finger, and centrifugally-controlled means pivoted to the center shaft and actuating the disk member.

3. A centrifugal speedometer comprising

in combination with a center shaft a dial plate, a pivotally-mounted speed indicating finger on the dial plate, means to secure said finger in adjusted position, gravity-controlled members operatively connected with and disposed parallel to the center shaft and centrifugally actuated members pivoted to the center shaft operatively connected with the aforesaid gravity-controlled members.

4. A centrifugal speedometer comprising centrifugal elements, a disk member supported by the centrifugal elements, a separator center shaft to which the centrifugal elements are pivoted and on which the disk

member is mounted, a connecting rod having its bottom end supported and actuated by the disk member, a graduated plate member, an adjustable speed-indicating finger pivotally mounted thereon, and means connecting the aforesaid finger with the above-mentioned connecting-rod, substantially as set forth.

In testimony whereof I hereunto affix my signature, in the presence of two witnesses. 25

MARTINUS H. G. OEDEKERK.
